His Attorney.

UNITED STATES PATENT OFFICE.

JAMES A. ROSE, OF ST. LOUIS, MISSOURI.

NON-GROUNDED SPARK-PLUG.

1,299,035.

Specification of Letters Patent. Patented Apr. 1, 1919.

Application filed January 11, 1918. Serial No. 211,351.

To all whom it may concern:

Be it known that I, JAMES A. ROSE, a citizen of the United States, residing at St. Louis, in the State of Missouri, have invented certain new and useful Improvements in Non-Grounded Spark-Plugs, of which the following is a specification containing a full, clear, and exact description, reference being had to the accompanying drawings, forming a part hereof.

My invention relates to spark-plugs which are used in firing the charge of explosive in the cylinders of automobile motors, air-plane engines, and in all other hydrocarbon power plants; and my invention consists in the novel construction and combination of parts hereinafter fully described and particularly pointed out in the claim found at the end of this specification.

Heretofore, in all spark-plugs known to me, one of the two points (between which the spark is formed) has been "grounded" to some portion of the engine, which acted as a conductor for electricity between the grounded point and the source of electricity, so that but a single terminal was provided at the top or exposed end of the plug, and if the flexible conductor became accidentally disconnected from said single terminal and, again accidentally momentarily connected therewith while the metallic part of the plug is in contact with some metallic portion of the engine, a dangerous spark has been produced between the two spark points of the plug, causing accidental explosions and damage.

The object of my invention is to provide a "non-ground" spark plug, which will obviate the danger of accidental explosions of gasoline vapor while the spark plug is detached from its usual position and carelessly placed in the vicinity of gasoline, with its "grounded" point electrically connected to a source of electricity, such as a magneto, battery, or dynamo.

In the drawings,

Figure 1 is a vertical section through my improved spark plug, and

Fig. 2 is a side-elevation of the point-carrying body of insulation, detached from the plug.

The numeral 1 designates the usual plug casing, which is made of metal, with a threaded end 2, for the well-known purpose of permitting the plug to be screwed into the combustion chamber of the engine.

A cylindrical body of suitable insulation (such as porcelain or mica) 3 is provided with an enlargement 4 at about the center of its length, and two point wires 5 and 6 are 60 molded, cast, or otherwise securely placed within said body (preferably during the molding operation), so that said wires will pass endwise through said body, and their lower ends project a distance beyond the 65 lower end of the body, as shown, to form thereat spark points 7 and 8.

To prevent longitudinal movement of the wires 5 and 6 in said body of insulation 3, I form a circular bend, or a "kink" 9 in said 70 wires at the point where said body is the largest and the strongest, which is within the said enlargement 4, thereby obviating as far as possible the weakening of said body by the said bend or kink in said wires. 75

The usual stuffing-box gland 10 is screwed into the upper end of said casing 1, to engage a suitable gasket or packing 11, to make a tight joint between said casing and the said body of insulation 3, which carries 80 both of said points.

The usual gasket 12 is also used to make a tight joint, and to make a soft or yielding seat for the said body of insulation's enlargement 4, at the point where said body 85 rests at the base of the socket in said casing.

The upper, or outer, end of the said body 3 is formed with an integral flat extension 14, which projects a considerable distance beyond the main body, and acts as a shield 90 to prevent a spark from jumping across the space between the terminals of the said wires 5 and 6, and said extension 14 also acts to brace the terminals, in a manner now to be described. 95

Set on the upper end of said body 3, on opposite sides of the said extension 14, are brass terminal-caps 15, which are semicircular in plan-view, and have integral screws 16 provided with clamping-nuts 17, by means 100 of which the wires from the magneto, battery or other source of electricity are connected to said terminal-caps, the caps themselves being connected to the upper ends of the said wires 5 and 6 by the ends of said wires being inserted through perforated ears 18 which depend from the underside of said caps, and said wires may be further and more securely connected to said ears by means of solder, or in any other known way, 110 preferably before the material of the said body 3 is molded around the wires.

The operation of my invention will be clear to those skilled in the art, without further description.

I claim:

- 5 An improved spark-plug, composed of a metallic casing, a body of insulation seated in said casing and having at one end a flat extension which projects a sufficient distance to act as a shield and brace for the terminals
10 of the plug; metallic terminal caps set on opposite sides of said extension and provided with suitable terminal clamps to receive the magneto or battery wires; and two separate point wires embedded in said insulation and extending through the same from end to end, and having ends which project
- 15

beyond the ends of said body of insulation, and form at one end spark-points, the opposite ends of said wires being connected to said terminal-caps on opposite sides of the 20 said extension of said body of insulation, and the said wires being provided with circular bends or kinks intermediate of their ends, to prevent their withdrawal from said insulation in which they are embedded.

In testimony whereof, I have signed my name to this specification in presence of two subscribing witnesses.

JAMES A. ROSE.

Witnesses:

FRANCES HOOVER ROSENBAUM,

JOHN C. HIGDON.
